UNITED STATES PATENT OFFICE

CLEMENT LEE DOWNEY, OF CINCINNATI, OHIO

COIN COUNTING AND ASSORTING MACHINE

Application filed May 10, 1927. Serial No. 190,309.

My invention relates to improvements in coin counting and assorting machines.

In my application for Letters Patent, Serial No. 32,275, of which this is a continuation in part, I have disclosed a machine for counting and assorting coins of different denominations. In this co-pending application I have disclosed a primary counting machine which is adapted to count in United States coins, dimes, pennies, nickels, and quarters. The coins are carried around on a rotatable disc set at an angle on an annular flange of the disc, and the coins are interspersed by pins extending up at right angles to the face of the disc. The coins are carried into engagement with a series of rotatable members, each of which actuates by the same movement both a counter and a coin chute through which each coin is discharged from the disc. There is a caliper plate which forces each different denomination of coin into engagement with a different rotatable member, and as the primary disc is arranged for counting in United States coins, dimes, pennies, nickels and quarters, there are four sets of rotatable members and four sets of coin chutes through which the coins pass. I have also disclosed in this co-pending case an auxiliary counting and assorting device which is adapted to count half-dollars. As far as I am advised, the combination of an auxiliary counting device for such coins as cannot, because of their size be taken care of on the primary disc is broadly new.

It is the object of my invention to provide a primary and secondary structure the combination of which will enable practically every denomination of coin which is coined in any country in the world, to be selected and counted. Thus, while I show only the combination with a primary and one auxiliary counter, the units may be increased in capacity and number so that the possible variations in the sizes of coins which may be counted are without limitation. A further object is the provision of a coin counting and selecting machine in which defective coins and slugs and tokens will not only not be counted, but in which coins which are bent out of shape or burred, will be caught prior

to their entrance into the coin selecting and counting portion of the machine in a position in which they may be removed without difficulty. The provision of a machine which will not be harmed by defective coins is a development of considerable importance. The above noted objects which possibly were inadequately disclosed in the aforenoted application, I accomplish by that certain combination and arrangement of parts of which the drawings show a preferred embodiment.

A further object of my invention, as disclosed herein, is the provision of a novel type of coin chute which will greatly lessen the driving power required to operate the machine, and which will cause less likelihood of coins sticking immediately prior to their discharge into a coin chute. It is another of my objects to provide a coin carrying disc which will not allow coins to be carried around in such positions that they might block the machine. A still further object is the provision of a novel type of coin carrying pin or lug which will prevent a coin or token having a hole in it from becoming wedged in the machine due to having been caught on a carrying pin. It is further my object to provide improvements in tripping mechanism for actuating the coin chutes.

Referring to the drawings:—

Figure 1 is a perspective view from in front of one of my machines showing a combination of one primary and one auxiliary counting device.

Figure 2 is a front elevation of a portion of the auxiliary coin counting and selecting disc with the guard plate for the larger size coin discharge opening removed.

Figure 3 is a side elevation with some of the parts removed showing the auxiliary and primary machine.

Figure 4 is a diagram from the rear of the belt drive for both the coin discs of both the auxiliary and primary selecting and counting mechanisms.

Figure 5 is a perspective view of the primary counting machine, the half-dollar counting device shown in Figure 1 having been disassembled.

Figure 6 is a plan view of the spring post and caliper supporting plate.

Figure 7 is a side elevation of the plate shown in Figure 6.

5 Figure 8 is a bottom plan view of the plate shown in Figures 6 and 7, with the caliper plate shown in attached position.

Figure 9 is a perspective view of the coin chute tripping cam and shaft.

10 Figure 10 is a perspective view of the coin operated member which actuates the cam trip and the counting devices.

Figure 11 shows the parts shown in Figures 9 and 10 in operative position.

15 Figure 12 is a diagrammatic view of part of the operating mechanism of the primary counter and selector, with one coin chute in operative position.

Figure 13 is an end elevation of one of the 20 coin chutes.

Figure 14 is a plan view of the coin chute shown in Figure 13.

Figure 15 is a bottom plan view of one of the coin chutes.

25 Figure 16 is a side elevation of the chute shown in Figures 13-15.

Figure 17 is a fragmentary sectional view of the carrying disc.

The auxiliary coin selecting and counting 30 device which is shown in Figures 1, 2 and 3, consists of a rotatable disc 1 having arms 2 extending from the outer periphery thereof between which all the denominations of coins to be counted and selected are carried from

35 the lower portion of the machine where they are held in such position that they will fall against the disc by the hopper 3, to the discharge portion of the device which is at the top. The disc 1 is mounted at an angle both

40 to the horizontal and to the vertical so that coins will not fall off the arms 2 and so that they will always start at the bottom and be carried upwardly one at a time.

Under the disc 1 there is an inclined plate 45 4 along which the coins are slidably moved by the arms or fingers 2. At the top of the auxiliary counter and selector there is an opening which I have indicated as the shaded area 5 through which all coins not larger than 50 a certain diameter fall into a hopper 6 which supplies the coins to the primary counter and assorter. In a machine for United States coins, half-dollars will be the only coins which do not fall through the opening 5.

55 These coins which are of larger diameter continue on around the disc being supported by an upper ledge 7 and a lower ledge 7a, which extends in peripheral alignment with the annular edge of the disc 1. I have shown 60 a motor 8 for driving the machine. A convenient drive for the auxiliary and primary discs is indicated diagrammatically in Figures 1 and 4. A shaft having a worm on it is driven by the motor, and a worm gear is

mounted on a shaft 8a which carries the driving pulley 8b. Each of the primary and auxiliary discs has a pulley 8c mounted on the shaft or axis of the disc. I may provide a belt drive from the pulley 8b. The belt 8d moves around the pulley 8b counterclockwise as seen from the front around a guide pulley 8e under the driving pulley 8c of the auxiliary disc in a clockwise direction then around the driving pulley 8c of the primary disc 75 over another guide pulley and then back to the pulley 8b.

The larger denominated coins, in the machine illustrated, the half-dollars are carried over the opening 5 being supported on 80 the ledges 7, 7a to a position where they are carried into engagement with a trip finger 9 which carries a pin 9a extending in the path of the coins. The finger 9 is mounted on a shaft 9b which carries a bevel gear 9c. An 85 other shaft 9d having a bevel gear 9e is driven by the gear 9c and a crank 9f on the shaft 9d rocks the counter 9g with each tripping of the finger 9 by a passing coin. Still further along, as shown in the drawing, underneath the guard plate 10 there is an aperture 10a of sufficient size for the larger 90 denomination of coins, in this instance half-dollars, to fall through. A chute and hopper 10b leads from this opening into a suitable 95 receptacle for collecting the coins which I have indicated by the coin box 11.

In combination with the primary counter and selector which I provide, the auxiliary mechanism allows a combination in one machine of mechanism which will permit mixed coins from dimes to half-dollars all to be dumped into the initial hopper 3 for selecting and counting. I have provided a primary counter which due to the fact that only 100 dimes, pennies, nickels and quarters may be counted on it with complete safety requires some combination of parts which will take care of half-dollars and large coins. This combination which enables the selecting and 110 counting of mixed coins from dimes to quarters and including half-dollars and those of a size larger than quarters is thought to be a distinct advance in the art. By utilizing the same combination and adding another auxiliary counting unit with a wider opening between the ledges of the rotating carrying disc, silver dollars may also be counted. I do not ordinarily, however, find this necessary, as silver dollars are so infrequently used 115 that they can be picked out before the coins are fed to the machine.

I have shown a tray 12 which has an opening 12a in it, which is supported in front of the hopper 3 so that the coins to be counted 120 may first be dumped onto the tray and then swept with the hand into the hopper.

The primary counting and selecting mechanism is composed of a rotatable disc 13 also set at an angle to both the vertical and hori- 130

zontal. The hopper guard plate 6 retains the coins at the bottom 14 in such position that they will fall against the disc. The disc has a ledge 15 on which the coins are carried around in a counterclockwise direction. At interspaced positions on the ledged portion I have provided a series of lugs 16 which have interspaced outer edges at such distances apart that the longest dimension of the pocket formed between the lugs is less than the sum of the diameters of two of the smallest coins to be counted. The reason that I have provided a lug instead of a set of pins is that manufacturers of tokens usually form apertures in the tokens by which they may be distinguished from coins. In case, therefore, that a token of similar size as a coin, and having an aperture therein, is mixed in with the coins to be counted, there is no likelihood of the token becoming wedged on top of a pin and carried around on it under the guard plate where it might block the machine. If coins of larger sizes than quarters are used on a machine handling dimes every 25 once in a while two dimes will become wedged between a pair of lugs and block the machine.

It will further be noted that the spaces 17 in radial alignment with the lugs 16 are beveled off. If the ledge 15 were continuous it 30 would sometimes happen that a coin would become caught on the ledge immediately adjacent a lug, and as the disc is set at an angle it might be carried in under the guide plate and thus block the machine. The provision 35 of the lugs as indicated and of the beveled portions in alignment with the lugs are thus shown to be safeguards against the passage of coins into such a position that they will not be immediately accessible for withdrawal.

It is a feature of my mechanism that a defective coin which is bent out of shape will be caught as it passes to the opening in the caliper guard plate, in which position it may block the machine and cause the belt to slip, 45 but as it will immediately be accessible to withdrawal, no serious injury can happen to the machine, and it will be visible to the operator.

In order to explain the construction of 50 the assorting and counting mechanism of the primary part of the machine, I will first describe the caliper guard plate 17a to which reference has been made in the immediately preceding paragraph. Figures 6, 7 and 8 show the preferred construction clearly. There are bosses 18 at each end of the plate which have holes 19 by which the plate is mounted in interspaced position from the disc. I prefer to support the plate by means 55 of threaded posts 20 in the frame 21 of the machine. The caliper plate 22 which is best shown in Figure 8 has a recessed portion 23 having holes by which the plate is secured to the supporting plate by screws 24. The 60 supporting plate has slots 25 which slidably

engage the coin chutes, and I find it preferable to secure individual interspacing plates such as are shown at 26 to fill in sufficient space between the supporting plate and the disc, so that a coin as large as a quarter if 70 slightly bent will not pass down along the caliper plate, but will be caught at the admission end which I have indicated at 27. Thus it will appear that any bent coin which, in all other coin counting and selecting machines of which I am advised, may get caught in an inaccessible position, which may require the entire dismantling of the machine, will be caught at the admission aperture under the plate, in which position it may be 75 readily removed.

In some convenient position where they may be readily observed by the operator of the machine, the counters for counting the coins as they are selected are mounted. I 80 have shown the set of counters for the dimes, pennies, nickels and quarters secured to the frame of the machine at 28, 28, etc. Each counter has a series of links which connect it with its respective counter trip. A counter 85 trip 29 is illustrated in Figure 10. Each counter trip consists of a shaft 30 which is journaled in the machine. There are four counter trips shown one for each denomination of coin. A segmentary portion 30a extends up from the frame of the machine and lies in the path of a coin. As each denomination of coin being guided tangentially from the ledge of the carrying disc by the caliper plate engages the upper edge of the 90 segment, the shaft 30 rocks thereby actuating the counter.

The coin chutes are formed in the shape of channels which have extensions 31 which are slidably engaged in the slots in the caliper supporting plate. The principle of operation is that coincidently with the rocking of the shafts 30, the coin chute extensions are lowered into engagement with the carrying disc and each respective coin then passes 100 down the chute into its respective coin receptacle. The extensions 31 are normally tensioned so that they will be pressed toward the disc. A convenient means of pressing the extensions of the coin chutes toward the disc 105 is provided in the swivelling spring posts. The spring posts have base portions 32 which are pivotally mounted as by the screws 33 in the supporting plate 17a. The bases have bosses 34 in which plunger pins 35 are 110 pressed downwardly by springs 36. When it is desired to remove the coin chutes from the slots, the knurled upper ends of the pins 35 are elevated and the lower portions thereof are removed from recesses 37 which are 115 formed in the supporting plate in alignment with each respective slot.

The coin chutes have bases 38 in alignment with the extensions 31 along which the coins roll edgewise. The bases and extensions are 120 125 130

mounted in the machine so that they will lie at substantially right angles to the face of the carrying disc. A cover plate 39 having peep holes 40 in it is attached to the base plate 38. With the machine operating at its normal capacity of nine hundred coins per minute if no cover plate is provided the coins will frequently be thrown out of the chute. The base plates have mounting pins 41 having slots 42 in which the bases are pivotally mounted. This mounting permits the spring posts to be swivelled and the coin chutes elevated from the position in which they are shown in Figure 1 to the position in which they are shown in Figure 5 without any disassembling of the machine.

I have observed that it is preferable not to have the plate along which the coins roll flatwise rigidly secured to the base. A preferable mounting for this plate 43 is shown in Figure 15. The plate has a block 44 at its pivoted end to which it is secured. The block is mounted on another block 45 which is attached to the base 38. A pivot pin 46 is connected between the blocks. At the intake end of the chute the plate 43 is resiliently supported by a spring 47 which is mounted in a recess 48 in another block 49 which is secured to the base plate as by means of the screws 50. In order to provide an adjustable mounting for the plate 43 I also prefer to attach to the plate 43 a bracket 51 which clears the plate, but has an end 52 in alignment with the under face of the block. I extend an adjustment screw 53 which may also have a lock nut 54 thereon through the end 52 and by turning the screw the end bears against the lower face of the plate 43 and thus regulates its position with relation to the base plate 38.

The block 49 has an extension 55 which is engaged by a cam trip 56 which I have shown in Figures 5, 9 and 11. The cam trip of which there are three in the primary machine, as the last coin chute for dimes does not need to be tripped, has a shaft 57 which is pivotally mounted in the machine frame. Each cam trip has an angular recessed portion 58 which engages the segmentary edge 59 of the counter trip. A plan view of the cam trip and the counter trip in operative engagement is shown in Figure 11. When the cam surface of the cam slides out from under the extension 55 of the coin chute the coin chute is temporarily depressed because each extension 31 of a base of a coin chute is pressed down by its respective spring post into engagement with the surface of the coin carrying disc, and the high points of the cams are all that hold the coin chutes up. Each coin therefore at practically the same moment when it trips the counter trip also actuates the cam trip and brings down the coin chute extension so that it will engage it and roll down the chute.

The resiliently mounted plate 43 at its end toward the carrying disc has an edge end 60 which lies substantially in peripheral engagement with the edge of the carrying disc while the surface of the plate 43 is in substantially parallel alignment with the surface of the carrying disc. I have found that if the plate 43 is rigidly attached to the coin chute that a ledge will be formed at end 60 against which the edge of a coin will occasionally catch and thus block the machine. In order to provide a more positive discharge which will practically never block a coin when once it has rotated the counter trip, I provide this resiliently supported plate 43 so that when the edge of a coin strikes the end edge of the plate 43, the plate will spring downward slightly allowing the coin to pass. The resilient mounting for the plate 43 also is noticeable in that the motive power required for driving the machine is thereby lessened.

After a coin has tripped the counter trip, and the counter trip has tripped the cam trip, the cam trip must then be returned so that it will support the coin chute in its normal interspaced position from the carrying disc. The means which I have provided for accomplishing this operation are as follows. It will be noted that the lugs on the carrying disc 13 are secured with screws to the disc. I extend one of the screws of each lug below the surface of the disc and as the underneath extension of each screw passes its respective cam trip it engages a rounded end 61 of the cam trip, thereby returning the cam trip and the counter trip into position to be engaged by the next following coin of its respective denomination. I have further found that the trips are less likely to catch and block if this return movement is aided resiliently. I have therefore provided resilient strips or wires of spring metal such as I have indicated at 62, and attached an end of a spring to the rounded portion of each cam trip. The other ends of the springs I have soldered to the machine casing so that the springs extend radially from the axis of pivotal movement of the cam trips, so that no matter which way the cams are moved, the springs will tend to move them in the other direction. The use of these springs, I find, greatly lessens the wear on the segmentary and angular engaging portions of the cam and counter trips and also more infrequently leads to one of the trips sticking and thus blocking the machine.

Another feature of my primary counting and selective mechanism is that a coin with an outer edge burred will stick without actuating the counter trip as the clearance between the segment and the extensions of the coin chute is insufficient to permit the coin to pass through. In this position the movement of the carrying lug will cause the coin to whirl around without discharging into the

coin chute. When this happens, the machine is blocked. The operator will learn of this occurrence when the belt starts to slip. He will then have to remove the plate 17a and 5 pick out the coin. Although a burred coin will not stop in the position 27 where it can be removed without any disassembling, the removal of the plate 17a is a simple task and the coin which should be withdrawn from circulation 10 may be removed.

I have explained in detail the mechanism of my coin counting and selecting machine in order to enable others skilled in the art to make use of my invention, but I nevertheless 15 reserve in the claims that follow what changes and mechanical modifications will readily occur to those skilled in the art by which equivalent objects may be accomplished by utilizing the principles which I 20 have disclosed.

Having thus described my invention what I claim as new and desire to secure by Letters Patent is:—

1. In a device of the character specified, a 25 rotatable disc provided with means for separately carrying coins of different diameters, a plurality of movable coin chutes, each for receiving coins of similar diameters, and a plurality of mechanical means, each for moving 30 a different coin chute into position to receive a coin carried on said disc.

2. In a device of the character specified, a rotatable disc provided with means for separately carrying coins of different diameters, 35 a plurality of movable coin chutes, each for receiving coins of similar diameters, a plurality of mechanical means, each for moving a different coin chute into position to receive a coin carried on said disc, and a plurality 40 of mechanical means, one for each coin chute, for moving said coin chutes out of coin receiving position.

3. In a device of the character specified, a rotatable disc provided with means for separately carrying coins of different diameters, 45 a plurality of movable coin chutes, each for receiving coins of similar diameters, a plurality of mechanical means, each for moving a different coin chute into position to receive 50 a coin carried on said disc, and a plurality of mechanical means, one for each coin chute, for moving said coin chutes out of coin receiving position, each set of means for moving coin chutes into position to receive a coin 55 and for moving said respective chutes out of coin receiving position including a common movable member.

4. In a device of the character specified, a rotatable disc provided with means for separately carrying coins of different diameters, 60 a plurality of movable coin chutes, each for receiving coins of similar diameters, a plurality of mechanical means, each for moving a different coin chute into position to receive a coin carried on said disc, and a plurality of

mechanical means, one for each coin chute, for moving said coin chutes out of coin receiving position, each set of means for moving coin chutes into position to receive a coin and for moving said respective chutes out of coin receiving position having a common 70 movable member, said first mentioned means operable by a coin carried on said disc and said second mentioned means operable by said separate coin carrying means. 75

5. A machine of the character described having a rotatable coin carrying disc, a plurality of devices associated with said disc each for receiving coins of different denominations, a plurality of means each for a 80 respective device for tripping said devices to induce their movement into position to receive coins, said means being mounted in spaced positions equidistant from the axis of said disc.

6. A machine of the character described having a rotatable coin carrying disc, a plurality of devices associated with said disc each for receiving coins of different denominations, a plurality of means each for a respective device for tripping said devices to induce their movement into position to receive coins, said means being mounted in spaced positions equidistant from the axis of said disc, and cam means for directing 90 coins carried on said disc into engagement with said tripping means. 95

7. A machine of the character described having a coin carrying disc, assorting means for receiving coins carried on said disc and 100 means for guiding coins into position to induce the actuation of said assorting means, said assorting means comprising a plurality of movable coin chutes each movable into a position to receive a coin of a different 105 denomination.

8. A coin assorting machine having a coin carrying disc, chutes arranged to be positioned to receive coins carried on said disc, each chute for receiving coins of a similar 110 denomination, cam means for guiding coins carried on said disc in accordance with their respective denomination into position to be received in their respective positioned chute.

9. A coin assorting machine having a coin carrying disc, chutes arranged to be positioned to receive coins carried on said disc, each chute for receiving coins of a similar 115 denomination, cam means for guiding coins carried on said disc in accordance with their respective denominations into position to be received in their respective positioned chute, and tripping devices for moving said coin chutes into coin receiving position. 120

10. A coin assorting machine having a 125 coin carrying disc, chutes arranged to be positioned to receive coins carried on said disc, each chute for receiving coins of a similar denomination, cam means for guiding 130 coins carried on said disc in accordance

with their respective denomination into position to be received in their respective positioned chute, tripping devices for moving said coin chutes into coin receiving position, 5 said machine being of the type having counters connected and arranged to register the numerical operations of said respective tripping devices.

11. A coin assorting machine having a 10 coin carrying disc, a plurality of means arranged at equal distances from the axis of said disc for receiving coins, each of said means movable to a position to receive coins of the same diameter, and means for guiding 15 coins, in accordance with their diameters respectively, different distances into position to be received by their respectively positioned coin receiving means.
